ENCLOSURE AND MAST SUPPORT FOR A TRANSMITTING ANTENNA

John F. Redman, Jr., 4311 W. 70th St.,
Prairie Village, Kans.

Filed Dec. 8, 1958, Ser. No. 53,675

Term of patent 14 years

(Cl. D26—14)

Fig. 1 is a side elevational view of an enclosure and mast support for a transmitting antenna, showing my new design, the appearance being substantially the same from all sides;

Fig. 2 is a fragmentary side elevational view, to a larger scale, portions of the mast being broken away for convenience in illustration;

Fig. 3 is a fragmentary side elevational view to a still larger scale; and

Fig. 4 is a top plan thereof, to an enlarged scale.

I claim:

The ornamental design for an enclosure and mast support for a transmitting antenna, as shown.
